TOOLS FOR INSERTING ARBORS IN WATCH
MAIN SPRINGSEdward James Renz, New York, N.Y., assignor to Ham-
mel Riglander & Company, Inc., New York, N.Y., a
corporation of New York

Filed July 6, 1962, Ser. No. 207,981

1 Claim. (Cl. 81—6)

This invention relates to means by which watch main springs can be readily and conveniently provided with a barrel arbor, and it consists of a device by which the central or inner convolution or loop of the main spring will be elevated and distended whereby the arbor can be easily fitted within the spring and engaged therewith.

It is an object of the invention to provide a device of this character arranged for the accommodation of springs of various sizes; which will accept springs provided with an encircling ring, and which will greatly facilitate the insertion of an arbor within the spring.

More particularly, the invention contemplates the provision of a plate or block that is provided in its upper surface with a plurality of spaced circular recesses of different diameters for the reception of main springs of different sizes. Centrally located on the base of each of the recesses is a conical, upstanding projection provided with a central hole or closed bottom deep recess. In operation, one of the main springs provided with an encircling annulus or disk is placed in the recess of required size, and the central convolution or loop of the spring, so positioned, will fit over the projection at the bottom of the recess, thereby causing the loop of the spring to be both slightly elevated and distended. In such elevated and distended position of the loop, the central part of the spring is made accessible to enable an arbor to be readily inserted within the loop and pressed down to engage the loop while one of the shaft portions of the arbor enters into the hole provided through the conical projection.

With these and other objects to be hereinafter set forth in view, I have devised the arrangement of parts to be described and more particularly pointed out in the claims appended hereto.

In the accompanying drawing, wherein an illustrative embodiment of the invention is disclosed,

FIG. 1 is a top plan view of a tool constructed according to the present invention;

FIG. 2 is an enlarged view of a part of the tool, showing one of the spring-receiving recesses therein;

FIG. 3 is a sectional view, taken substantially on the line 3—3 of FIG. 2, looking in the direction of the arrows;

FIG. 4 is a vertical sectional view through a part of the tool showing how the same receives a main spring and positions it for the reception of an arbor;

FIG. 5 is a plan view of a main spring provided with its encircling collar or ring, and

FIG. 6 is an edge view of the spring and its encircling ring.

In the drawing, 1 generally indicates a watch main spring, the same in the form shown, consisting of a spirally wound strip confined in its wound condition by means of an encircling collar or ring 2 which serves to hold the spring from unwinding and facilitates its subsequent insertion in a barrel. The inner end of the spring is formed with a loop or convolution 3 usually provided with an

2

aperture, not shown, for engagement by a tooth 4 provided on the central barrel portion 5 of an arbor 12 which is adapted for insertion within the loop or inner convolutions 3 of the spring.

5 The encircling collar or ring 2 is in the form of an annular disk and it may be composed of metal or plastic and it serves to surround and hold the spring 1 in its coiled condition substantially as shown in FIGS. 5 and 6 and it is supplied to the watchmaker in such condition by the manufacturer.

10 The improved tool consists of a flat plate or block 6 provided in its upper surface with a plurality of circular, relatively shallow recesses or depressions 7, the same being graduated in size for the accommodation of main springs of various sizes. The plate or block 6 may be made in various sizes and the number of recesses employed in it may be increased or decreased to meet requirements.

15 Extending centrally and upwardly from the base surface 8 of each of the recesses 7 is a conical projection or elevation 9 formed with a central hole or deep closed-bottom recess 10, said hole or recess being adapted for the reception of the shaft portion 11 of the arbor 12 when the arbor is fitted within the central convolution or loop 3 of the main spring.

20 25 Each of the conical projections 9 is relatively small compared to the overall size of each recess 10 in which the projection is located so that an annular spacing is provided between the conical projection and the side wall of the recess to thereby accommodate all the convolutions of the spring and the encircling collar 2, the central convolution 3 being the only convolution engaged by the projection 9.

30 35 In the use of the tool, the watchmaker selects a recess 7 of the required size and the spring 1, provided with the encircling collar 2 are placed in the recess substantially as shown in FIG. 4, bringing the central convolution or loop 3 of the spring over the raised conical projection 9 on the bottom surface of the recess. As the spring is pressed downwardly, the tapered shape of the conical projection will tend to raise the loop 3 slightly and at the same time it will expand or spread the same.

40 45 The arbor 12, which may be held in a suitable tool, is now inserted within the loop or convolution 3 to bring its part 5 therein and when turned slightly it will force the loop portion 3 down against the conical projection and expand it further so that the arbor can easily enter the loop and the tooth 4 on the arbor caused to engage the recess in the loop 3. As the arbor is forced into position as above described, its shaft portion 11 will enter the hole or recess 10 and will thus be prevented from being damaged during the attachment of the arbor to the main spring.

50 55 The provision of a plurality of differently-sized recesses 7 in the base block or plate 6 provides the watchmaker with a universal tool useful for main springs of many different sizes and the provision of the springs with a flat encircling collar enables the springs to be easily handled and fitted into and removed from the recesses 7 in the block after the application of the arbor.

60 65 Having thus described a single embodiment of the invention, it is obvious that the same is not to be restricted thereto, but is broad enough to cover all structures coming within the scope of the annexed claim.

What I claim is:

65 A tool for fitting an arbor in a watch main spring in

which the spring has an encircling member consisting of a disk-shaped annulus, the improvement consisting in a block having a circular recess formed in it, said recess having a central, conical, raised projection for engaging only the inner loop on the spring when the spring and its encircling member are inserted within the recess, the recess having a relatively wide annular spacing between the base of the conical projection and the side wall of the recess to therein accommodate the convolutions of the spring other than the inner loop thereof which is engaged by the projection, the projection having a central recess

for receiving the shaft of an arbor when the arbor is fitted within the central loop of the spring.
